[57] CLAIM

The ornamental design for a wheel, as shown and described.

DESCRIPTION

FIG. 1 is a front elevation view of a wheel showing my new design;

FIG. 2 is a rear elevation view thereof;

FIG. 3 is a sectional view thereof taken along line 3—3 in FIG. 1;

FIG. 4 is a front perspective view thereof;

FIG. 5 is a front elevation view of a wheel showing a second embodiment of my new design;

FIG. 6 is a rear elevation view of FIG. 5;

FIG. 7 is a sectional view taken along line 7—7 in FIG. 5; and

FIG. 8 is a front perspective view of FIG. 5.

FIG. 3

FIG. 4

FIG. 6

FIG. 7

FIG. 8
